UNITED STATES PATENT OFFICE.

LUCILLE BENTZ, OF SEATTLE, WASHINGTON.

DESIGN FOR A SOUVENIR-SPOON.

45,367.

Specification for Design.

Patented Mar. 10, 1914.

Application filed July 3, 1913. Serial No. 777,330. Term of patent 3½ years.

To all whom it may concern:

Be it known that I, LUCILLE BENTZ, a citizen of the United States, residing at Seattle, in the county of King and State of Washington, have invented a new, original, and ornamental Design for Souvenir-Spoons, of which the following is a specification, reference being had to the accompanying drawing, forming part thereof.

The figure is a plan view of the souvenir spoon, showing my new design. Handle representing a raven, bear and whale; bowl of spoon representing an Indian in canoe.

I claim:

The ornamental design for a souvenir spoon, as shown and described.

LUCILLE BENTZ.
